UNITED STATES PATENT OFFICE

104,466

DESIGN FOR A BOOK COVER

Leonard Mounteney, Chicago, Ill., assignor to Consolidated Book Publishers, Inc., Chicago,
Ill., a corporation of Illinois

Application March 25, 1937, Serial No. 68,402

Term of patent 7 years

To all whom it may concern:

Be it known that I, Leonard Mounteney, a citizen of the United States, residing at Chicago, in the county of Cook and State of Illinois, have invented a new, original, and ornamental Design for a Book Cover, of which the following is a specification, reference being had to the accompanying drawing, forming a part thereof:

The figure is an elevational view in open position of my new book cover.

I claim:

The ornamental design for a book cover, as shown.

LEONARD MOUNTENEY.
